UNITED STATES PATENT OFFICE.

WILLARD OHLIGER, OF DETROIT, MICHIGAN, ASSIGNOR TO FREDERICK STEARNS & COMPANY, OF DETROIT, MICHIGAN, A CORPORATION OF MICHIGAN.

MACHINE FOR CUTTING WAFER-CAPSULES.

1,097,727.

Specification of Letters Patent.

Patented May 26, 1914.

Application filed September 24, 1912. Serial No. 722,155.

To all whom it may concern:

Be it known that I, WILLARD OHLIGER, a citizen of the United States of America, residing at Detroit, in the county of Wayne 5 and State of Michigan, have invented certain new and useful Improvements in Machines for Cutting Wafer-Capsules, of which the following is a specification, reference being had therein to the accompanying drawing.

The invention relates to multiple cutting dies and is particularly designed for use in the manufacture of wafer-capsules.

It is the object of the invention to provide 15 means for cutting individual capsules from a sheet with which they are integral, and to accomplish this result without injury to the capsules which are exceedingly fragile.

To this end the invention consists in the 20 construction as hereinafter set forth.

In the drawings: Figure 1 is a vertical central section through the machine; and Fig. 2 is a perspective view thereof.

In the manufacture of wafer-capsules, one 25 method employed is to spread a plastic composition, such as a starch compound, between hot die plates to form a sheet having a multiple of the capsules integral therewith. Subsequently the individual capsules must 30 be cut from the sheet, and the usual method is to cut them individually by a pair of cutting dies. The present construction is designed to simultaneously cut all of the capsules from the sheet, thereby effecting a great 35 economy of time.

A is a suitable frame, upon which is mounted a punch plate B, having a multiple of punch members C distributed over the plate and exactly positioned for registration 40 with the capsules in the multiple sheet. These capsules are usually of a dish-shaped form, having a central depressed portion and an annular marginal flange. In the multiple sheet the peripheral lines of the 45 flanges are not defined, but these form integral portions of a connecting web. The punches C are therefore of a diameter corresponding to the diameter of the flanges of the capsules, and to provide clearance for 50 the depressed portion of the capsule, each punch is provided with a recess D.

E is a die plate which is apertured to receive the punches C and in coöperation therewith sever the capsules from the connecting 55 web of the sheet. This die plate is prefer-

ably actuated by a spring F which engages a cross-bar G attached to guides H, which slidably engage bearings I on the frame. Normally the plate E is in raised position and is spaced from the punch plate B a sufficient 60 distance for the insertion of the wafer sheet therebetween.

To engage the wafer sheets with the cutting dies and to insure exact registration therewith, said sheets are first subjected to a treatment for altering the moisture content of the compound, this, however, forming no part of the present invention. When in proper condition the sheets may be successively registered with the punch plate, but it 65 is essential that the web shall be brought in contact with the punches before the cutting operation; as otherwise there is danger of breaking or destroying the marginal flanges of the capsules. I have therefore provided 70 means for insuring this firm contact which consists of a suction apparatus for drawing the sheet into contact with the punches or dies. As shown, the frame A has a chamber J formed in the upper portion thereof beneath the punch plate B, and which is connected by a conduit K, controlled by a valve L, with a suitable vacuum apparatus, not shown. Each of the punches C is centrally 75 apertured to place the recess D therein in communication with the chamber J and consequently whenever the valve L is open a suction will be produced in each of the recesses D. Thus if the wafer sheet is first 80 placed in substantial registration with the punch plate the suction will draw the individual depressed portions of the capsules into their respective recesses D, thereby 85 bringing the web portion of the sheet into firm contact with the punches C, so that 90 when the die plate E is released the spring F will draw it downward and simultaneously 95 sever the capsules from the web of the sheet.

For operating the die plate E suitable 100 mechanism is provided for raising it after each operation, together with a trip mechanism for releasing the plate when the cutting is to be effected. Still further provision is made for disengaging the cut capsules 105 from the recesses D after the severing operation. As shown, M is a drive-wheel upon a shaft N, which through the medium of a pinion O communicates continuous rotary motion to a gear-wheel P sleeved upon an intermittently rotating shaft Q. This shaft is 110

intermittently connected to the gear-wheel by a clutch R (not shown in detail), and controlled by a trip-lever S, the arrangement being such that when tripped the clutch will couple the gear-wheel to the shaft Q, imparting one complete revolution to the latter, whereupon the clutch is again released. Upon the shaft Q is a cam T, which engages a roll U upon a rock shaft U', having rock-arms U² extending into engagement with the cross-bar G. The cam T is of a spiral form and normally is in a position where the large portion thereof is in engagement with the roll U, thereby holding the cross-bar G through the medium of the rock-arm U² in a position where the guides H and die plates E are raised. At one point in the cam T is an abrupt drop T', which, when motion is imparted to the shaft Q, will suddenly release the plate E by permitting the springs to draw it downward as before described.

For disengaging the capsules a stripper-plate V is arranged within the chamber J, this being provided with a series of pins W respectively engaging the apertures connecting with the recesses D in the punches. In normal position of the plate V the pins W are withdrawn from the recesses D and therefore do not interfere with the engagement of the capsules therewith. The plate V has a central shank X passing through a bearing X' in the bottom wall of the chamber J and extending into the path of a lug Y on the cross-bar G. Thus when the cam T is revolved, the rock-arms U² will raise the cross-bar G a sufficient distance to actuate the shank X, raising the plate V and causing the pins W to disengage all of the cut capsules. This operation is effected by a high point T² in the cam T, after passing which the cam drops away to permit the withdrawal of the pins W into their normal positions.

In operation, the wafers are successively placed in registration with the punch plate B, the valve L being then opened to put on the suction and the trip S being subsequently actuated to effect the cutting. At the completion of the cutting operation the pins W disengage all of the capsules, and by reason of the fact that the punch plate is arranged in an inclined plane, the severed capsules will fall off from said plate on to a belt and carrier Z or other device for receiving them.

To strip the web sheet from the punches a second stripper-plate V' is arranged above the punch plate B, being actuated by the stripper-plate V which engages depending lugs V² thereon. Thus the web of the sheet is disengaged from all of the punches, and the operator is permitted to withdraw it

from between the dies before he inserts an unpunched sheet.

65

What I claim as my invention is:

1. The combination of a multiple punch having recesses in the individual members thereof for receiving embossed portions of an integral sheet to be severed, means for engaging the embossed portions of said sheet with said recesses by suction, and a multiple die plate for coöperating with said punch to sever the sheet.

2. The combination of a multiple punch and coöperating die, the individual punch members being recessed to receive embossed portions of the sheet to be severed, suction means operable in advance of the operation of the punch and die for engaging said embossed portions with said recesses, a stripper for disengaging the severed members from said recesses subsequent to the operation of the punch and a second stripper-plate, operating to disengage the web of the sheet from the punches.

3. The combination with a supporting plate, of a plurality of punches projecting from said plate, each being provided with a central recess for receiving an embossed portion in the sheet to be severed, a vacuum chamber formed beneath said plate having communication with each of the recesses in said punch, a stripper-plate within said vacuum chamber having pins adapted to be projected into said recesses, a stripper-plate above said punch plate surrounding the punches thereof, a coöperating die-plate, means for producing suction in said vacuum chamber in advance of the operation of the punch and die, and mechanism for operating said punch and die and strippers in sequence.

4. The combination of a supporting frame, a plurality of punches supported upon said frame, a stripper-plate surrounding said punches, a vacuum chamber in said frame beneath said punches and communicating with recesses formed in said punches, a stripper-plate in said vacuum chamber, having pins projecting upward in said recesses, a coöperating die member, slideable guides for said die member, a cross bar connecting said guides, a rod extending from said pin-supporting stripper-plate into the path of said cross bar, and a cam for operating said cross bar to cause the actuation of said die member, and through the latter operating said stripper-plate.

In testimony whereof I affix my signature in presence of two witnesses.

WILLARD OHLIGER.
